C. H. NORTON.
WHEEL FEED FOR GRINDING MACHINES.
APPLICATION FILED JUNE 19, 1909.

982,628.

Patented Jan. 24, 1911

UNITED STATES PATENT OFFICE.

CHARLES H. NORTON, OF WORCESTER, MASSACHUSETTS, ASSIGNOR TO NORTON GRINDING COMPANY, OF WORCESTER, MASSACHUSETTS, A CORPORATION OF MASSACHUSETTS.

WHEEL-FEED FOR GRINDING-MACHINES.

982,628.

Specification of Letters Patent. Patented Jan. 24, 1911.

Application filed June 19, 1909. Serial No. 503,156.

To all whom it may concern:

Be it known that I, CHARLES H. NORTON, a citizen of the United States, residing at Worcester, in the county of Worcester and 5 State of Massachusetts, have invented a new and useful Wheel-Feed for Grinding-Machines, of which the following is a specification.

This invention relates to a feed for the 10 wheel of a grinding machine.

As now operated when grinding machines are used for grinding crank-shafts the work is not fed longitudinally, but the wheel is moved laterally directly up to the work, 15 and in this case the operator's hands are both busy so that he is unable to control the feed of the grinding wheel except through the automatic arrangements with which these machines are usually provided.

20 The principal object of this invention is to provide a simple and convenient mechanism taking up very little room by which the operator can personally control the feed of the grinding wheel without using his 25 hands for that purpose.

Further objects and advantages of the invention will appear hereinafter.

Reference is to be had to the accompanying drawing, in which

30 Figure 1 is a front view of a portion of a grinding machine showing this invention applied thereto; Fig. 2 is an end view of a portion of the same; and Fig. 3 is a transverse sectional view of part of the grinding 35 machine to which the invention is shown as applied.

This grinding machine is illustrated as comprising a bed 10 on which the work centers 11 are supported. On these work 40 centers is carried the crank shaft or other work which is to be ground. Mounted on the bed is a support or casing 12 for the grinding wheel 13 and this is movable directly toward and from the work by means of a nut 45 14 and a screw 15. This screw is operated by a gear 16 which in turn is operated by a pinion 17 connected with a ratchet wheel 18. This ratchet wheel is shown as provided with a handle 19 and micrometer adjustment 50 20 but these do not constitute a part of this invention. Mounted on the bed near the ratchet wheel are ways 21 for a sliding block 22 carrying a pawl 23 which as it moves up slides freely over the teeth of the 55 ratchet wheel and operates the latter as it

moves down. For operating the block 22 an arm 25 is shown pivoted on the frame at 26 and having thereon an adjustable block 27 provided with an adjusting screw 28 connected with a forked link 29 having a rack 30 thereon meshing with a pinion 31 on a crank disk 32 which is connected with the block 22 by a pitman 33. Also mounted on the arm 25 out beyond the block 27 is a fixed pin 35 which is received in a slot 36 65 in a head 37 adjustable on a link 38. This link slides in guides 39 on the bed and is connected with link-work shown in the present instance as comprising a bell-crank 40 and link 41. The link-work is connected 70 with a treadle 42 which is mounted in bearings supported by the bed, one of which is located on a bracket 43 mounted at the bottom of the bed. This bracket extends up at the end of the treadle and projects outwardly from the bed and carries a spring 44 which is connected with the treadle and which is intended to normally keep it in raised position.

When the treadle is depressed it moves 80 the link 38 to the left carrying with it the link 29. This moves the pawl 23 upwardly and allows the same to pass idly over the teeth of the ratchet wheel, thus having no effect on the grinding wheel. Then when 85 the foot is removed the spring acts to return the treadle to normal position which pulls down the pawl and yieldingly turns the ratchet wheel and moves grinding wheel. In this way it has been found in practice 90 that a very large amount of time is saved, particularly in the grinding of crank-shafts and similar articles which are ground in the same way, and that the operation of this kind of a wheel feed does not take the attention of the operator away from the work which he has to perform with his hands in grinding articles of this character.

While I have illustrated and described a preferred embodiment of the invention I 100 am aware that many modifications thereof can be made therein by any person skilled in the art without departing from the scope of the invention as expressed in the claims. Therefore I do not wish to be limited to all 105 the details of construction shown and described but

What I do claim is:—

1. In a grinding machine, the combination 110 with the bed, a grinding wheel movable

- laterally on the bed toward and from the work, an arm pivoted on the bed, and means connected with said arm for feeding the grinding wheel when the arm moves, of a 5 sliding link connected with the arm and guided on the bed, and a foot-treadle connected with said link and pivoted on said frame.
2. In a grinding machine, the combination 10 with the bed, a grinding wheel movable thereon, and means for adjusting the grinding wheel toward and from the work, said means comprising a rotatable toothed wheel, and a movable pawl for turning the wheel 15 when it moves in one direction, and an arm pivoted on the bed and having means thereon for operating the pawl, of a link pivoted on the arm, a foot-treadle mounted near the bottom of the bed and so connected with 20 the link as to cause the pawl to move idly over the wheel in one direction when the foot-treadle is depressed, and a spring for raising the foot-treadle and moving the link so as to give the pawl its operative stroke on 25 the ratchet wheel.
3. In a grinding machine, the combination with the bed, a grinding wheel movable thereon, a ratchet wheel and a pawl for operating it, of an arm pivoted on the bed, 30 a link adjustably connected with said arm and adapted to operate the pawl as the arm swings, a pin on the end of the arm, a link having an adjustable head provided with an open bottomed notch for engaging over the 35 pin to transmit motion to the arm, the connection of the first named link and arm being between the pin and pivot thereof, and a foot-treadle for operating the last named link.
4. In a grinding machine, the combination 40 with a bed, a grinding wheel movably mounted thereon, and means on the bed
- for adjusting the grinding wheel toward and from the work, of an arm pivoted on the bed, an adjustable block on the arm, 45 means connected with said block for operating the wheel-adjusting means, a leverage system connected with said arm beyond said block, a bracket on the bottom of the bed, a treadle on the bracket connected with said 50 leverage system, said bracket having an upwardly projecting portion extending out at the side of the foot-treadle, and a spring depending therefrom and connected with the foot-treadle to return it to normal position. 55
5. In a grinding machine, the combination with the bed, a grinding wheel movable laterally on the bed toward and from the work, an arm pivoted on the bed, and means connected with said arm for feeding the 60 grinding wheel when the arm moves, of a sliding link connected with the arm and guided on the bed, and a foot-treadle connected with said link pivoted on said frame, and yielding means for moving the foot-treadle so as to yieldingly feed the grinding wheel toward the work.
6. In a grinding machine, the combination with a bed having means for supporting the work, a grinding wheel laterally movable toward and from the work, means for feeding the grinding means toward the work, yielding means for operating the feeding means to feed the wheel laterally toward the work, and a treadle for distending the 65 yielding means.

In testimony whereof I have hereunto set my hand, in the presence of two subscribing witnesses.

CHARLES H. NORTON.
